**ARTICULATED JOINT UNIT FOR HINGING
TWO MEMBERS TOGETHER**

Charles R. Bacca, Milford, Ohio

Application December 9, 1953, Serial No. 397,216

11 Claims. (Cl. 312—242)

This invention relates to an articulated joint unit for hinging two members together, such as a door and support, and the combination of the hinged door and support, and it particularly pertains to a metal wall cabinet, having back, top, bottom and sidewalls forming an open front chamber or recess, and a swinging door for opening and closing the open front of said chamber or recess in the cabinet.

Conventional medicine cabinets are stamped from sheet metal to form a back wall with marginal surrounding top, bottom and sidewalls disposed at an angle to said back wall extending from one face to provide a recess or chamber having an open front opposite to the back wall. The free ends of the top, side and bottom walls are bent outwardly to provide a front face edge portion, generally parallel with the back, and also bent backwardly, generally parallel with the top, bottom and sidewalls into a surrounding flange which forms a channel, back of the front face edge, open at the rear of the cabinet. These cabinets are constructed to be inserted in a wall recess with the free edge of the flange abutting against the wall surrounding the wall recess. Accordingly, the free end of the flange terminates somewhat short of the vertical plane of the back wall to be of less depth than the overall depth of the cabinet.

A door is hinged to the front of the cabinet for opening and closing the recess or chamber in which several shelves are placed. A latch is fixed to the non-hinged side of the door to latch with the cabinet, and an accessory stop is ordinarily provided for holding the door ajar in a limited open position.

Heretofore, the hinge has been of conventional construction with one flap or strap attached to one side margin of the door and the other flap or strap attached to the cabinet adjacent one side edge of the chamber or recess. A conventional latch is provided on the opposite free side of the door to be detachably engaged with a yieldable catch on the cabinet. For holding the door in a limited open position, one end of a bar is pivoted to the top of the door, on the inside, with its opposite end carrying a collar or head adapted to engage a perforated clip fitted to the inside top wall of the cabinet and through which the rod slides.

With a conventional hinge, the latch and stop bar are necessary accessories for holding the door closed or ajar, and these not only are expensive and complicated but there is the problem of having them accurately fitted for efficient operation. Even though these parts may be accurately fitted at the time of manufacture, they frequently get out of alignment during the life of the cabinet, particularly the latch, and are not easy to adjust. The stop bar is objectionably noisy in sliding through the clip when the door is opened and closed.

Accordingly, one of the objects of the invention is a hinge which is simple in construction and efficient in operation for performing its functions as a hinge and additional functions as well.

Another object of the invention is a hinge which is

2:

adapted to be mounted on the rear side of the support to be substantially concealed from view from the front of said support at all times and under all conditions.

Another object of the invention is a hinge construction which will perform all the functions of the hinge, the stop bar and the latch.

Another object of the invention is a hinge provided with a limit stop means to define a range for the pivotal movement.

10 A still further object of the invention is a hinge provided with a frictional clamping means for dampening the movement of the door and frictionally holding it in any position to which moved.

Still another object of the invention is a hinge adapted 15 to be fixed to the bottom and top ends of the door for being hinged thereto rather than at one side thereof.

Further objects, and objects relating to details of construction and economies of operation, will readily appear from the detailed description to follow. In one instance

20 I have accomplished the objects of my invention by the device and means set forth in the following specification. My invention is clearly described and pointed out in the appended claims. Structures constituting preferred embodiments of my invention are illustrated in the accompanying drawings, forming a part of this specification, in which:

Fig. 1 is a front perspective view of the medicine cabinet, with the door open, provided with a hinge embodying the invention.

30 Fig. 2 is a top plan view of the hinged corner of the cabinet with a top portion of the door cut away.

Fig. 3 is a rear elevation view of the cabinet.

Fig. 4 is a detailed view of the hinge unit.

Fig. 5 is an exploded perspective view of the hinge unit.

35 Fig. 6 is a detailed view of another embodiment of the invention showing a frictional thrust bearing or seat and a limit stop formed on the hinge for defining the range of pivotal movement.

Fig. 7 is a detailed view, similar to Fig. 6, with the parts 40 of the hinge in limit stop position when the door is in extreme open position.

Fig. 8 is an exploded perspective view of the hinge unit and the holed portion of the flange of the support with which the hinge is associated.

45 The invention, generally described, comprises a pin or rod bent to provide one terminal end adapted to be fitted to a door, and also bent at its opposite end to provide another terminal end fitted to the cabinet, these end terminals being bent at an angle from an intervening connecting offset portion. One end of this rod is fitted to the door, and the door is hung on the cabinet with the offset portion of the rod seated on the end of the cabinet or a seat or bearing provided thereon with its opposite end projecting through a hole in the flange of the cabinet and provided with a sectional frictional clamp operated by a spring longitudinally coiled about said rod in a compressed condition between the clamp and a means for adjusting the compression of the spring. There are two of these hinge units for each cabinet, one unit being disposed at the top and the other unit being disposed at the bottom of the cabinet for hanging the door to the cabinet. A spring and limit stop is provided for at least one of the hinge units and preferably for both.

50 The frictional means functions to hold the door in any open position to which it is moved, and also to hold it closed. No latch is needed unless it is desired to latch the door closed.

55 Referring specifically to the drawings in which like numerals are used to refer to like parts, the invention is illustrated in connection with a conventional bathroom or medicine wall cabinet comprising a cabinet 1 formed from sheet metal and a door 2, carrying a mirror 3, pivoted

thereto. The door is also formed from sheet metal. The mirror is of plate glass secured to the front side of the door by a channel edging strip 4 encircling the peripheral edges of the door and mirror. The cabinet is of conventional form with its marginal flange 5 bent back from the face portion 6, forming the front edge of the cabinet, parallel with the wall 7. This results in a U-shaped channel 8 between the flange and the side and end walls opening towards the rear side of the cabinet. The cabinet is ordinarily seated in a wall recess, formed in the building wall, with the edge 9 of the flange 5 abutting a portion of the wall surrounding the wall recess. Conventional shelves are adapted to be provided in the cabinet, supported at their opposite ends by channel supports 11 fixed in position on the opposite sidewalls of the cabinet.

The above described cabinet and door are of conventional construction except in so far as being modified for having the hinge unit, hereinafter described, fitted thereto for hanging the door. The hinge construction is such as to hold the door in any desired open or closed position. Accordingly, no other means is needed for this purpose in addition to the hinge unless it be desired to have the door latched shut, in which event any conventional latch may be provided.

The hinge unit (Figs. 1 to 5) comprises a pintle rod of any suitable material having an intermediate offset portion 12 between its two opposite terminal ends 13 and 14, each of which is bent at an angle to the offset portion. One end 13 is inserted through a hole 15 in the door to snugly fit between the edging strip 5 and the edge of the mirror 3. This end of the rod is preferably flattened. The opposite end 14 of the rod is projected through a hole 16 in the marginal flange 5 at the top or bottom of the cabinet and extends a substantial distance therebeyond. A rotatable seat or bushing 17 of any suitable material is preferably fitted to the cabinet by being inserted within the hole 16 and disposed with one end in abutting relation with the offset portion of the rod. It may be made integral with or separate from the pintle rod. The reduced neck 18 of the seat or bushing fits the hole in the flange for the head or main part of said bushing to seat on the flange. This bushing is used for seating the offset portion 12 of the pin rather than have it seat directly on the flange since the swinging of the offset would mar the paint applied to the cabinet if it were in direct contact with the flange. Accordingly, this bushing may properly be considered a part of the cabinet even though made as a separate part. It is loosely mounted in the hole so as to turn relatively to the cabinet. It is recessed at 19 for the offset portion of the pin to fit therein and be caused to turn with the pin. However, the recess 19 could be omitted and the bushing made non-rotatable in respect to the flange, thereby permitting the top face of the bushing to provide a bearing surface on which the offset portion 12 swings. Or a washer could be interposed between the offset 12 and the top of bushing 17, said washer being provided with the recess 19 for seating the offset and turning with the pivot rod.

A clamp sleeve of any suitable material, comprising a plurality of segments or sections 20, is disposed about the pin, each of the segments of the sleeve having an inclined portion 21 on its outer wall and adjacent the top end. These are recessed at 22 to loosely receive the reduced neck 18 of the bushing 17 and align them end to end, said reduced neck 18 being of a length somewhat in excess of the thickness of flange 5 in order for it to extend into the recess 22 of section 20. A metal spring 23 is longitudinally coiled about the sleeve segments and compressed with one end seated against the inclined portion 21 on the sleeve and the opposite end seated against a nut 24 on the end of the pintle rod. Accordingly, the compressed spring 23 holds the segments tightly clamped radially against the pintle rod by reason of the inclined portions 21, and the end of the sleeve is held in frictional engagement with the flange 5. With the spring

5 compressed between nut 24 and the flange 5, the offset portion 12 of the pin is held closely in the recess 19 in the end of the bushing 17 and the end of the bushing is held in frictional contact with the flange to retard the swinging movement of the door. If a washer was interposed between the top of the bushing and the offset, the adjacent surfaces would be in frictional contact in addition to the frictional contact of the bushing with the flange.

10 There is a hinge unit for each end of the door with the door hung between them. The pintle rods do not need to be secured to the door other than by having the ends thereof inserted through the holes therein.

15 The hinged edge of the door is so positioned that it will abut against the flange 5 when the door is opened at about a ninety degree angle as shown in Figs. 1 and 2. A rubber stop bumper or bumpers 25 may be fitted to the flange 5 similar to bumpers 26 on the front face portion 6 in position to be contacted by the hinged end of the 20 door when opened to its extreme position. Or the bumpers may be placed on the door to engage the flange 5 of the cabinet.

25 In the embodiment of Figs. 6 to 8, the frictional resistance to the pivotal movement of the hinge parts is obtained by a thrust bearing comprised of a plurality of rings or washers 30 and 31 through which the angular end 14 of the pintle rod or pin projects. This end 14 of the pin or rod is of a non-circular cross section conforming to the non-circular conformation of the hole 32 in the washer 30 for it to be rotatable with the pintle pin or rod. This washer 30 has an ear 33 terminating in a depending lug 34, and it is superimposed on the washer 31 which is non-rotatable in respect to the pintle pin or rod by reason of an ear 35 terminating in the depending lug 36 which projects through a hole 37 in the flange of the cabinet. The under washer 31 is seated on top of the flange of the cabinet and the other washer 30 is superimposed thereon with the hole therein in registration with hole 15.

30 Another ring or washer 38, with a hole 39 therein, is placed on the underside of the cabinet flange on top of a washer 40 which is identical with washer 30. This washer 38 has an ear 41 with the hole 39 therein positioned to receive the depending lug on the ear 35, thereby holding it also non-rotatable in respect to the pintle rod or pin. The ring 38 performs the same function as ring 31, and hence there is a double stop means provided with each pintle pin or rod.

35 The hole 37 in the flange of the cabinet can be properly placed to have the ear 35 in desired position to be engaged by the lug 34 on the ear 33 for causing the door to be opened to any selected stop limit position.

40 A coiled spring 23 is inserted, surrounding the end of the pintle rod or pin, between the washer 40 and a nut 45 24 to be screw-threaded to the end of said rod or pin. The compression of the spring can be regulated by the nut to cause the adjacent faces of the rotatable and non-rotatable washers to be in frictional contact, thereby dampening their relative movement to frictionally hold the door closed or opened in any selected position less than extreme open stop position.

45 It will be appreciated that the non-rotatable washers or rings are used to reinforce the cabinet flange and represent any suitable means for this purpose. They are functionally a part of the cabinet. The rotatable washers are functionally part of the pintle rod and may be connected thereto in any suitable manner to rotate with it. The limit stop typifies one of any construction formed on the relatively movable parts, the duplication of the rings or washers on the opposite side of the cabinet flange is preferred but no indispensable.

50 From the foregoing description it will become readily apparent that the hinge units are fitted to the door by simply inserting one end thereof through the hole provided in the door for its insertion. No other means is

necessary for securing the rods to the door, they being securely held in place when the door is hung on the cabinet. The swinging movement of the door is frictionally damped by the frictional contacting faces of the washers or bearings or by the clamp sleeve which is radially compressed against the rod, and also spring pressed against the cabinet flange. The door can be manually moved in any selected position to be frictionally held in place. The frictional sleeve and friction contacting washers not only function to dampen the swinging movement of the door and hold it in any adjusted position, but prevents it from being easily slammed open and shut. The compression of the spring can be of any desired predetermined degree to regulate the frictional grip of the compressible sleeve with its contacting parts or the frictional grip between the contacting faces of the washers.

While the sleeve is preferably radially compressible for clamping the pin, it need not necessarily be of such construction, such radially compressible construction being for it to frictionally clamp the pin to dampen the swinging movement of the door. The hinge unit is of novel construction with or without the clamp sleeve. So, too, the non-rotatable washers may be fixed in any manner to the cabinet to be non-rotatable in respect to the pintle pin or rod and the rotatable washers may be associated in any manner with the pintle rod or pin to be rotatable therewith. All of the washers are longitudinally movable in respect to the pintle pin or rod. However, the non-rotatable washers may be considered a part of the cabinet, and the rotatable bearing sleeve and the rotatable washers may be considered as a part of the pintle pin or rod.

It will be understood that there may be various changes in details of construction without departing from the spirit of my invention, and, therefore, I claim my invention broadly as indicated in the appended claims.

Having thus described my invention, what I claim as new and useful and desire to secure by United States Letters Patent, is:

1. A medicine cabinet having a back, top and bottom sidewalls forming a main body portion adapted to be inserted in a wall recess, top and bottom rearwardly extending flanges on the top and bottom walls adapted to overhang and abut against the wall surface, and a door hinged to the cabinet by hinges fitted to the door and provided with extensions adapted to be pivoted within holes formed through the top and bottom flanges, said hinges including a pin projecting through the holes in said flanges, a thrust bearing fitted to one of the pins, and a spring mounted on said pin for providing frictional thrust.

2. A medicine cabinet having a back, top and bottom sidewalls, top and bottom flanges substantially parallel with the top and bottom sidewalls and spaced therefrom to provide a channel opening towards the back of the cabinet, a door hinged to the cabinet, and a hinge for the door comprising a pin having an intermediate offset portion between opposite ends that are bent at angles thereto, one of said angular ends of the pin being fitted to the door and the other angular end of the pin projecting through a hole in the flange of the cabinet with the offset portion of the pin adjacent said flange, and seating means on the cabinet engaging end of the pin for the offset portion of said pin, said hinge being provided with a stop for limiting the open position of the door and including relatively movable parts having frictionally engaging surfaces to dampen the pivoted movement.

3. A wall cabinet and door hinged thereto comprising a sheet metal cabinet having a stamped out-set-back rear wall surrounded by top, bottom and side walls forming an open chamber, a facial front edge for said top, bottom and side walls, a top and bottom flange extending rearwardly, generally parallel to the top and bottom walls, a door hinged to the cabinet for opening and closing the chamber, a top and bottom hinge for the door, each hinge

comprising a pintle rod fitted to the door and to the cabinet flange, a ring fitted to each pintle rod adjacent the outer side of the cabinet flange having a face surface in frictional contact with said flange, a compressed spring mounted on the pintle rod between the inner side of the cabinet flange and a seating means on said pintle rod for holding the spring compressed, and a limit stop carried by said pintle rod for engaging with a cooperating limit stop carried by the cabinet.

4. The wall cabinet and hinged door of claim 3 in which a ring is interposed between each of the other rings having a mating surface in frictional contact therewith and is secured to the cabinet flange to be non-rotatable in respect to the pintle rod, and another ring interposed between the spring and the cabinet flange.

5. A medicine cabinet having a back, top and bottom sidewalls, top and bottom flanges substantially parallel with the top and bottom sidewalls and spaced therefrom to provide a channel opening towards the back of the cabinet, a door hinged to the cabinet, and a hinge for the door comprising a pintle rod having an intermediate offset portion between opposite ends that are bent at angles thereto, one of said angular ends of the rod being fitted to the door and the other angular end projecting through a hole in the flange of the cabinet with the offset portion of the rod adjacent the flange, a sectional bearing mounted on the pintle rod composed of a plurality of superimposed washers with at least two washers interposed between the offset of the pintle rod and the flange and with at least one on the opposite side of the flange, the washers adjacent the flange being non-rotatable relatively thereto and the washer remote from the flange being rotatable with the pintle rod, stop means disposed on the hinge for limiting its pivotal movement, and spring means for yieldably holding the superimposed washers in frictional contact.

6. A wall cabinet having a back, top, bottom and side walls forming an open front chamber, a facial edge surrounding the chamber and terminating in rearwardly extending top and bottom flanges, a pintle rod fitted to each of the top and bottom ends of a door, hinged to the cabinet, and provided with a projecting end adapted to be fitted to the cabinet, a recess formed in the top and bottom cabinet flanges through which the projecting ends of the pintle rods are inserted, a thrust bearing on one of the rods adjacent one side of the cabinet flange, a washer disposed on the rod adjacent the opposite side of the cabinet flange, and a spring for urging the washer and thrust bearing towards each other and against the opposite sides of said flange.

7. The wall cabinet of claim 6 in which the spring is compressed between said washer and an adjustable means carried by the rod.

8. A support and door hinged together at their top and bottom ends comprising a door, a support with top and bottom rearwardly extending flanges, a pintle rod holding means provided on the top and bottom rearwardly extending flanges, a pintle rod for each pintle rod holding means having one end fitted to the door and its opposite end engaged with said pintle holding means, said rod having an intervening portion disposed adjacent one side of the flange, and a spring mounted on the rod between a means fitted thereon adjacent the opposite side of the flange for urging the intervening portion of said rod towards the flange.

9. The hingedly connected door and support of claim 8 in which a rearwardly open channel is formed on the rear side of the support adjacent one side of the support between the rearwardly extending top and bottom flanges, and the spring on the pintle rods are in said channel.

10. A wall cabinet and door hinged thereto comprising a sheet metal cabinet having stamped out set-back rear wall surrounded by top, bottom and side walls forming an open chamber, a facial front edge for said top, bottom and side walls, a top and bottom flange extending

ing rearwardly, generally parallel to the top and bottom walls, a door hinged to the cabinet for opening and closing the chamber, a top and bottom hinge for the door, each hinge comprising a pintle rod fitted to the door and to the cabinet flange, a ring fitted to each pintle rod adjacent the outer side of the cabinet flange having a face surface in frictional contact with said flange, a compressed spring mounted on one of the pintle rods between the inner side of the cabinet flange and a seating means on said pintle rod for holding the spring compressed, and a stop for limiting the pivotal movement of the door from closed to open position.

11. A wall cabinet and door hinged thereto comprising a sheet metal cabinet having a stamped out set-back rear wall surrounded by top, bottom and side walls forming an open chamber, a facial front edge for said top, bottom and side walls, a top and bottom flange extending rearwardly, generally parallel to the top and bottom walls, a door hinged to the cabinet for opening and closing the chamber, a top and bottom hinge for the door, each hinge comprising a pintle rod fitted to the door and to the cabinet flange, a ring fitted to each pintle rod adjacent the outer side of the cabinet flange having a face surface in frictional contact with said flange, a compressed spring mounted on the pintle rod between the

inner side of the cabinet flange and a seating means on said pintle rod for holding the spring compressed, and a stop for limiting the pivotal movement of the door from closed to open position.
